UNITED STATES PATENT OFFICE.

EVA TYNER, OF CANON CITY, COLORADO.

FOLDING FRAME FOR MOSQUITO-BARS.

976,950.

Specification of Letters Patent. Patented Nov. 29, 1910.

Application filed March 28, 1910. Serial No. 552,037.

To all whom it may concern:

Be it known that I, EVA TYNER, a citizen of the United States, residing at Canon City, in the county of Fremont and State 5 of Colorado, have invented certain new and useful Improvements in Folding Frames for Mosquito-Bars, of which the following is a specification, reference being had to the accompanying drawings.

10 My invention relates to improvements in frames or supports for mosquito bars or net canopies, and its object is to provide a simple and practical device of this character which may be compactly folded when not in use, 15 and which may be readily set up and used on a baby's crib, a bed, a table or other object for supporting a netting or canopy which will exclude flies, mosquitos and other insects.

20 With the above and other objects in view, the invention consists of the novel construction, combination and arrangement of parts, hereinafter fully described and claimed, and illustrated in the accompanying drawings 25 in which:

Figure 1 is a perspective view of my improved folding frame in its open position; Fig. 2 is a transverse sectional view, the mosquito bar or canopy being indicated in 30 dotted lines; Fig. 3 is a detail section taken on the plane indicated by the line 4—4 in Fig. 2; Fig. 4 is a detail perspective view of the sliding catch; and Fig. 5 is a plan view of the frame folded.

35 My improved folding frame or support for net canopies or mosquito bars comprises two similar side members 1 united by inwardly folding end members 2. The side members 1 are each formed from a single 40 piece of heavy wire or metal rod by bending it at suitable points to provide straight central portions 3 and downwardly and outwardly inclined portions 4, which latter form supporting legs.

45 The end members 2 are each formed of two hingedly connected half sections 5, 6, which are hingedly connected to opposing legs 4 and adapted to fold inwardly to bring the two side members 1 close together so 50 that the frame when folded will occupy but little space. The half sections 5, 6, are each formed from a single piece of heavy wire bent into U-form and having their closed or connecting portions 7 forming pivots and 55 united by a sheet metal hinge loop 8. The

extremities of the parallel arms of the U-shaped sections 5, 6, are bent to form hinge eyes 9 which latter engage and rotate on the legs 4, as shown more clearly in Figs. 2 and 3.

60 In order to prevent the end members 2 from collapsing when the frame is set for use I provide on each of said members a sliding catch or fastener 11 which is constructed from a suitable piece of sheet metal 65 and has a tubular end 12 to slide on one of the arms of one of the half sections of said member, and the other end of said fastener 11 being channel or U-shaped, as shown at 13, and adapted to slide over and engage 70 the corresponding arm of the opposing section of the end member when such member is in open position, as will be understood on reference to Figs. 1 and 2.

75 In order to prevent a mosquito bar or net canopy, which is indicated at A in Fig. 2, from sagging in the center of the frame, cords, wires, chains or similar flexible elements 14 are arranged diagonally between the corners of the side members 1. These 80 elements 14 are attached to eyes or hooks formed preferably from pieces of wire 15 which are bent around and secured to the upper portions of the legs 4 immediately beneath the upper hinge eyes 9, whereby these 85 wire hooks serve not only as attaching means for the cords or elements 14, but also as stops for preventing the end members from slipping downwardly on the legs 4. The cords or elements 14 will, of course, drop within 90 the frame when the latter is folded or collapsed.

95 From the foregoing it will be seen that my invention provides an exceedingly simple and inexpensive frame which will effectively support a mosquito bar over a bed or crib, or a net canopy over a table or any other object. The peculiar construction of the device not only enables it to be produced at a small cost but permits it to be quickly 100 and easily set up for use or folded for storage or transportation. When set up for use and fastened it will be exceedingly rigid and effectively support the mosquito bar or canopy.

105 While the present embodiment of the invention is especially designed for use on a baby's bed or crib to support a mosquito bar or any canopy or cover over the child and out of contact with him, it will be under- 110

stood that the device may be used for supporting a net canopy over a dining table and for various other purposes.

Having thus described the invention, what is claimed is:

1. A device of the character described comprising two side members each formed from a piece of wire by bending it at suitable points to provide a central portion and depending legs, inwardly folding end members composed of half sections, each of the latter being formed from a piece of wire bent into U-form and having the extremities of its arms bent to form hinge eyes which engage the legs, a hinge strap uniting the closed portions of the two U-shaped half sections, a sliding catch for each end member mounted for sliding movement on one half section of the same and having a channel portion to engage the opposing half section, and flexible elements between the two side members.
2. A device of the character described comprising two side members each having side bars and downwardly extending legs, inwardly folding end members each composed of hingedly connected half sections, the latter having at their outer ends eyes to loosely engage the legs, whereby said sec-

tions are hingedly connected to the legs, flexible elements to support a mosquito bar or canopy at the central portion of the frame, and attaching means for said elements arranged on said legs beneath the eyes on the sections of the end members, whereby said fastening means for the elements will prevent the end members from slipping downwardly on the legs.

3. A device of the character described comprising two side members each formed from a piece of wire by bending it at suitable points to provide a central portion and depending legs, inwardly folding end members composed of half sections, each of the latter being formed from a piece of wire bent into U-form and having the extremities of its arms bent to form hinge eyes which engage the legs, a hinge strap uniting the closed portions of the two U-shaped half sections of each end member, and catches for locking the end members in open position.

In testimony whereof I hereunto affix my signature in the presence of two witnesses.

EVA TYNER.
